[57] CLAIM

The ornamental design for a combined baseball game and pieces therefor, as shown and described.

DESCRIPTION

FIG. 1 is a perspective view of a combined baseball game and pieces therefor, showing my new design, with some of the game pieces shown removed;

FIG. 2 is a top plan view thereof;

FIG. 3 is a front elevational view thereof;

FIG. 4 is a rear elevational view thereof;

FIG. 5 is a left side elevational view thereof; and

FIG. 6 is a right side elevational view thereof.

The bottom view is plain and unornamental.

FIG. 1

FIG. 2

FIG. 3

FIG. 4

FIG. 5

FIG. 6
